UNITED STATES PATENT OFFICE

109,438

DESIGN FOR A BIB-APRON

Dorothy Steele Neely, Los Angeles, Calif.

Application August 18, 1937, Serial No. 71,158

Term of patent 14 years

To all whom it may concern:

Be it known that I, Dorothy Steele Neely, a citizen of the United States, residing at Los Angeles, in the county of Los Angeles and State of California, have invented a new, original, and ornamental Design for a Bib-Apron, of which the following is a specification, reference being had to the accompanying drawing, forming part thereof.

The figure is a front elevational view of a bib-apron, showing my new design.

I claim:

The ornamental design for a bib-apron, as shown.

DOROTHY STEELE NEELY.
